(57) **CLAIM**

The ornamental design for a condom package, as shown and described.

DESCRIPTION

FIG. 1 is a perspective view of a first embodiment of a condom package showing the new design.

FIG. 2 is a top view thereof;

FIG. 3 is a left side view thereof;

FIG. 4 is a bottom view thereof;

FIG. 5 is a right side view thereof;

FIG. 6 is a top view thereof;

FIG. 7 is a bottom view thereof;

FIG. 8 is a perspective view of the second embodiment of the condom package;

FIG. 9 is a top view thereof;

FIG. 10 is a left side view thereof;

FIG. 11 is a bottom view thereof;

FIG. 12 is a right side view thereof;

FIG. 13 is a top view thereof;

FIG. 14 is a bottom view thereof;

FIG. 15 is a perspective view of the third embodiment of the condom package;

FIG. 16 is top view thereof;

FIG. 17 is a left side view thereof;

FIG. 18 is bottom view thereof;

FIG. 19 is a right side view thereof;

FIG. 20 is a top view thereof; and,

FIG. 21 is a bottom view thereof.

The broken lines in the Figures show portions of the condom package which form no part of the claimed design.

1 Claim, 18 Drawing Sheets
